J. BERGEN.

Wheel-Cultivator.

No. 64,061.

Patented Apr. 23, 1867.

United States Patent Office.

JACOB BERGEN, OF CANTON, OHIO.

Letters Patent No. 64,061, dated April 23, 1867.

IMPROVEMENT IN CULTIVATORS.

The Schedule referred to in these Letters Patent and making part of the same.

TO ALL WHOM IT MAY CONCERN:

Be it known that I, JACOB BERGEN, of Canton, in the county of Stark, and in the State of Ohio, have invented certain new and useful improvements in Cultivators; and do hereby declare that the following is a full, clear, and exact description thereof, reference being had to the accompanying drawings, and to the letters of reference marked thereon.

In the annexed drawings, making part of this specification, A A represent the two side pieces of the frame, which are connected together by means of six cross-pieces, B B, these side and end pieces forming the frame of the machine. D D represent two short crank-axes, upon which are secured the wheels E E. These axles are provided with suitable journal boxes, by means of which they are connected to the under side of the frame. These axles act independently of each other, so that one side or the other of the machine may be lowered to suit the nature of the ground. H H represent levers, which are secured to the axles for the purpose of moving them so as to raise or lower either side of the machine. These levers pass between guides I and J. One of said guides is provided with slots or openings, α α , into which lugs upon the levers catch, for the purpose of stationing the levers at any desired point. Each lever is provided on one side with a spring, d, which spring working against the guide J, serves to press the lever H against guide I, forcing the lug upon it to enter one of the openings in said guide I, when it comes opposite it. G G represent reversible cultivator teeth, which are bolted on to the lower ends of the two bars F F, at the point where said bars are welded together. F F represent two metallic bars, which have their lower ends flattened, sharpened, and curved forward, and then welded together. Their upper ends are separated so as to pass through two of the cross-pieces B B. They are provided with nuts upon their ends above the cross-pieces to hold them securely in position. The tongue C lies upon the frame and is bolted fast to it.

I am aware that a divided axle of itself is not new, hence I do not claim it; but what I do claim, is—

The arrangement of the crank axles D D, with the levers H, spring d, and guides I and J, substantially as and for the purpose specified.

In testimony that I claim the foregoing I have hereunto set my hand and seal this 18th day of February, 1867.

JACOB BERGEN.

Witnesses:

JACOB MENGER,

GEO. W. RAFF.
